UNITED STATES PATENT OFFICE.

ALONZO G. DECKER, OF TOWSON, MARYLAND, ASSIGNOR TO THE BLACK AND DECKER MANUFACTURING COMPANY, OF TOWSON, MARYLAND, A CORPORATION OF MARYLAND.

DESIGN FOR A CASING FOR AN ELECTRIC HAMMER OR SIMILAR ARTICLE.

Application filed December 14, 1927. Serial No. 24,478. Term of patent 14 years.

To all whom it may concern:

Be it known that I, ALONZO G. DECKER, a citizen of the United States of America, residing at Towson, Baltimore County, Maryland, have invented a new, original, and ornamental Design for a Casing for an Electric Hammer or Similar Article, of which the following is a specification, reference being had to the accompanying drawing, forming part thereof.

Figure 1 is a side elevation of the casing showing my new design.

Figure 2 is an end elevation looking from the left in Figure 1.

I claim:

The ornamental design for a casing for an electric hammer or similar article, as shown.

Signed by me at Towson, Maryland, this December, 1927.

ALONZO G. DECKER.
